Primary Examiner — John R Yeh

(57) **CLAIM**

The ornamental design for an automotive cleaning brush, as shown and described.

DESCRIPTION

FIG. 1 is a front, top perspective view of an automotive cleaning brush, showing my new design;

FIG. 2 is a rear, bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof; and,

FIG. 9 is a front, top perspective view of the automotive cleaning brush of FIG. 1 in a partially folded configuration. The broken lines show portions of the automotive cleaning brush that form no part of the claimed design.

The dashed lines in the figures illustrate portions of the automotive cleaning brush that form no part of the claimed design.

1 Claim, 9 Drawing Sheets
